DESIGN FOR A HANGING LAMP.

SPECIFICATION forming part of Design No. 14,408, dated November 13, 1883.

Application filed July 2, 1883. Term of patent 7 years.

UNITED STATES PATENT OFFICE.

WOLCOTT A. HULL, OF NEW YORK, N. Y., ASSIGNOR OF ONE-HALF TO THE ANSONIA BRASS AND COPPER COMPANY, OF SAME PLACE.

DESIGN FOR A HANGING LAMP.

SPECIFICATION forming part of Design No. 14,408, dated November 13, 1883.

Application filed July 2, 1883. Term of patent 7 years.

To all whom it may concern:

Be it known that I, WOLCOTT A. HULL, of New York, in the county and State of New York, have invented a new and useful Design 5 for a Hanging Lamp, of which the following is a specification.

The design relates to the "harp" or frame of a hanging lamp.

The accompanying illustration is a perspective view of a lamp embodying my design.

A designates the harp or frame. It consists of a rod or tube bent longitudinally into circular or approximately circular form. As shown, this rod or tube is round in the cross-section. At the center of the lower portion of the harp or frame a pull-piece, B, extends from it. This pull-piece is ring-shaped. Its lower portion, a, is striated, its side portions are embellished with scroll-shaped figures b, 20 and its upper portion is ornamented with scroll-shaped figures c. From the frame A extend two angular ornaments, C. Each has a curved lower edge and an upright side. At the junction of the bottom and side is a button 25 or rosette, d, and at the top of the side portion is a foliate figure, e. The body of each of the ornaments C is embellished with a flower, f,

leaves g h, and a scroll figure, i. The surface j between these figures is roughened.

What I claim as my design, and desire to 30 secure by Letters Patent, is—

1. The harp or frame A, of curved form, having angular ornaments C, substantially as shown and described.

2. The harp or frame A, of curved form, 35 provided with angular ornaments having curved bottoms, and upright sides terminating in foliate figures e, substantially as shown and described.

3. The harp or frame A, of curved form, 40 having angular ornaments C, embellished with leaves and flowers, substantially as shown and described.

4. The harp or frame A, of curved form, 45 provided with the angular ornaments C, having curved bottoms, upright sides terminating in foliate figures e, roughened surfaces j, flowers f, leaves g h, and scroll figures i, substantially as shown and described.

WOLCOTT A. HULL.
